UNITED STATES PATENT OFFICE

CLARENCE O. SHUNK AND MATTHIAS REDLINGER, OF FREEPORT, ILLINOIS

PRY PLATE

Application filed November 19, 1928. Serial No. 320,255.

Our invention relates to pry plates of the kind adapted to be attached to the side of freight cars between the open door and the sheathing to provide, a metal bearing or bite 5 for lever or pinch bars used in closing the doors, whereby the siding of the car is protected from the destruction caused by driving the bar therein for a like purpose.

It is well known that the doors of cars of 10 this description are handled only with the greatest difficulty. Handles are ordinarily provided for drawing the doors open and closed along the tracks provided for the purpose but it is rarely possible to move them 15 by these agencies. In order, therefore, to close the door a bar having a sharp point is driven into the siding at a point as near the rear edge of the door as possible. The opposite end of the bar is then swung forward 20 against the edge of the door, pinching it forward a small amount. This movement is continued until the door has been moved inch by inch into the closed position, leaving a trail of points where the bar has been inserted 25 into the siding, causing material damage. This practice soon necessitates replacement of the sheathing covered by the side doors. This involves not only the expense incident to materials and labor but also the temporary 30 retirement of the car from service and the resulting increase of the number of cars necessary to the business.

The general object of our invention is to 35 provide improved means for protecting the sheathing of a wooden freight car from the destructive action of a pinch bar or the like used in urging the side doors of box cars shut, comprising a formed metal strip attached to the side of the car in a position convenient for 40 the use of a pinch bar.

We have also aimed to provide a formed metal strip adapted to be attached to a car having metal siding to cooperate with a bar 45 in closing the side doors of the same.

Other objects and advantages of our improved construction will appear to those skilled in the art from the following description and the accompanying drawings in 50 which—

Figure 1 is a fragmentary elevation of a box car embodying our invention;

Fig. 2 is a section on the line 2—2 showing the pry plate and car door with a pinch bar inserted in the manner of operation;

Fig. 3 is a top view of a portion of the pry plate, and

Fig. 4 is a side elevation of the pry plate.

Referring to Fig. 1, the side of a box car is designated generally by 5 and a sliding door of the usual type by 6. The door is shown equipped with the usual handle 7 and hasp 8 and is adapted to slide from the closed position shown to an open position with its edge resting against the brackets 9. Guides 10 at the bottom edge of the door prevent it from swinging outward. The pry plate is designated generally as 11.

The details of the plate are perhaps best shown in Figs. 3 and 4. The plate comprises an essentially flat strip of metal having regularly spaced outwardly bowed portions 15 each of which has a rectangular tongue 16 cut therein. The end 17 of the tongue is cut transversely across the center of the strip at 75 the outermost point 20 of the bowed portion. The tongue portions and those portions of the strip 18 which lie intermediate the bowed portions are coplanar and are adapted to lie flush against the side of the car. The plate 80 is provided with centrally located holes 19 between each succeeding bowed portion for attaching the plate.

Referring now to Fig. 2 where the numerals given have the same significance, the pry 85 plate is shown attached to the side wall of a conventional wood sided car by means of bolts 12. The edge of the door 6 is provided with a customary protecting angle plate 13. A pinch bar 14 is shown to illustrate the manner in which the various parts cooperate. When the pry plate is used in moving the door the operations are essentially the same as when the door is moved without it except for the fact that the bar need 90 not be driven into the side wall of the car to provide a bite. The edges 20 and sections 21 of the plate formed by cutting the tongues from the outwardly bowed portions offer effective and readily accessible bearing points 100.

for the end of the bar. The point of the bar, therefore, need only be inserted into the depressions left by the tongues and the angle of the bar brought over against the door plate 5 13 to bring the bar into a position whereby the door may be pinched forward. A single throw of the bar will bring the door far enough forward to uncover the next succeeding bowed portion where the operations are repeated. By a succession of similar operations the door is brought to the closed position without damaging the car.

Attention is directed to a number of features which serve to make our construction especially practical and durable in use and inexpensive in manufacture and application. The edges 20 formed by cutting out the ends 15 of the tongues serve as bearing edges for the end of the pinch bar, the outward bend of the metal acting to draw the bearing edges away 20 from the wall and well up on the end of the pinch bar. However, were the edges 20 extended completely across the plate, there would be a tendency, in the case of very obstinate doors, for the raised sides 15 to be 25 bent upward and perhaps be broken off. In our construction greater strength is obtained through sections 21 defined by the outer edges 30 of the pry plate and the tongues cut therein. These sections prevent the sides 15 from being displaced. It will also be seen that the tongues are not merely incidental to the formation of the bearing edges 20 and the strengthening sections 21, but in themselves 35 serve an important purpose. Examination of Fig. 2 will show that when the bar is inserted against the bearing edges 20, were it not for the tongues 16 which serve as protective abutments the end of the bar would 40 come in contact with the side of the car and a certain amount of damage thereto result. The tongues, however, completely protect the wood beneath since no matter in what position the bar stands it is prevented from 45 contact with the side of the car.

Further, when a flat plate of metal is attached to the side of a wooden box car moisture collects and is held between the plate and sheeting causing the sheeting to decay. 50 In the application of our pry plate this objection is overcome by the outwardly bowed portions which permit access of air to a large portion of the sheeting which would normally be covered by the metal whereby the moisture is removed by evaporation.

The construction is also adapted for use upon steel sided cars to permit the use of 55 pinch bars in closing the doors. The plate will here offer the same advantages for prying purposes though perhaps not necessary for the protection of the car.

While we have described a particular embodiment of our invention in some detail we are aware that numerous changes may be 60 made without departing essentially there-

from and we do not wish to be limited except by the spirit of the invention and the appended claims, in which—

We claim:

1. A pry plate for freight car doors and the 70 like comprising a metal strip having regularly spaced outwardly bowed portions each of which has a tongue cut therein.

2. A pry plate as set forth in claim 1 in which each tongue is rectangular and the 75 end is cut transversely across the outermost point of the bowed portion.

3. A pry plate as set forth in claim 1 in which the tongue portions and those which 80 lie intermediate the bowed portions are coplanar and adapted to lie flush against the side of a car.

4. A pry plate for freight car doors and the like comprising a metal strip having bearing edges pressed up at regularly spaced intervals and intermediate abutment portions, the bearing edges providing bites for a pry 85 bar and the abutment portions protecting the side of the car from the point of the pry bar.

5. A pry plate for freight car doors and 90 the like adapted to be attached to the side of a car between the car and the open door comprising a metal strip having regularly spaced transversely raised bearing portions adapted to receive the end of a pry bar, marginal 95 strengthening portions, coplanar portions between the first mentioned portions comprising transverse sections adapted to rest against and receive means for attaching a strip to a car, and longitudinal tongue portions extending to points beneath the bearing portions adapted to limit the inward movement of the end of the bar, the whole serving to provide a bearing for a pry bar and preventing its contact with the car wall while a door 100 is being closed by operation of the bar.

6. A pry plate for freight car doors comprising a metal strip adapted to be attached to the side of a car between the open door and the car and having regularly spaced outwardly bowed portions alternated with coplanar portions, each of said outwardly bowed portions having three sides of a rectangular tongue cut therefrom, said tongue 115 lying in the plane of the coplanar portions and being adapted to rest against the side of a car to protect the same, one side of said cut passing transversely across a portion of the strip at the outermost point in the bowed portions, said transverse cut being adapted 120 to receive the end of a lever bar when the door is being closed.
